UNITED STATES PATENT OFFICE.

ROBERT W. GEE, OF MONTPELIER, IDAHO.

GATE-LATCH.

988,455.

Specification of Letters Patent. Patented Apr. 4, 1911.

Application filed October 27, 1910. Serial No. 589,417.

To all whom it may concern:

Be it known that I, ROBERT W. GEE, a citizen of the United States, residing at Montpelier, in the county of Bear Lake and State of Idaho, have invented certain new and useful Improvements in Gate-Latches; and I do declare the following to be a full, clear, and exact description of the invention, such as will enable others skilled in the art 10 to which it appertains to make and use the same.

This invention relates to improvements in gate latches.

One object of the invention is to provide 15 an improved gate latch adapted to automatically fasten the gate when swung to a closed position.

Another object is to provide a latch having a keeper adapted to be adjustably secured to the latch post of the gate to compensate for any sag in the gate or leaning of the latch post.

With the foregoing and other objects in view the invention consists of certain novel 25 features of construction, combination and arrangement of parts as will be more fully described and particularly pointed out in the appended claim.

In the accompanying drawings: Figure 1 30 is a side view of a portion of a gate and a latch post showing the application of my improved latch; Fig. 2 is a front elevation partly in section of the keeper plate of the latch; Fig. 3 is a similar view of the latch 35 plate and pin; Fig. 4 is a detail perspective view of the latch pin; Fig. 5 is a horizontal sectional view on the line 5—5 of Fig. 1.

In the embodiment of the invention I provide a latch plate 1 on the outer side of 40 which are formed upper and lower laterally projecting pin supporting lugs 2 in which are formed alined passages with which is slidably engaged the latch pin 3. The lugs 2 may be formed in any suitable manner but 45 are here shown as being cut from the metal and bent outwardly at right angles to the plate.

The latch pin 3 consists of a rod of sufficient length to project above and below the 50 lugs 2. The projecting upper end of the rod is bent into a horizontally disposed loop to form a handle 4 while the lower end of the pin projects a sufficient distance below the lower lug to engage the keeper herein- 55 after described. In the pin 3 below the upper lug 2 is formed an eye through which

is adapted to be inserted a cotter pin 5 or any other suitable form of pin whereby a stop is provided which, when the pin is raised will engage the upper lug 2 and thus 60 prevent the pin from rising so far as to disengage the lower end thereof from the lower lug 2. In the pin 3 adjacent to the lower end thereof is formed a second eye 5' with which is adapted to be engaged any suitable 65 form of locking pin or padlock (not shown), but by means of which the pin may be locked in engagement with its keeper hereinafter described thereby fastening the gate 70 in closed position.

The latch plate 1 is provided with elongated screw holes or slots 1^a adapted to receive fastening screws whereby the plate may be adjustably secured to the gate.

The keeper for the latch comprises a plate 75 6 having formed on its upper end a right angularly projecting keeper or latch lug 7 which is provided with a centrally disposed elongated pin receiving aperture or slot 8 with which the lower projecting end of the 80 pin is adapted to be engaged when the gate is swung to a closed position. The lug 7 has its side edges turned down or inclined as at 9 whereby when the gate is swung to a closed position and the end of the pin thus 85 brought into engagement with the latch lug the inclined surface of the lug will lift the pin thus permitting the gate to swing to a full closed position at which time the end of the pin will engage and drop into the 90 aperture 8 in the lug thereby securely latching the gate in closed position. When it is desired to open the gate the handle of the pin is grasped and the latter drawn upwardly out of engagement with the lug 7 of 95 the keeper, thus permitting the gate to be swung open in either direction. If it should be desired to lock the gate in closed position a cotter pin or padlock may be engaged with the aperture 5' in the lower end of the pin 100 below the lug 7 of the keeper thus preventing the raising or disengagement of the latch pin from the keeper.

The keeper plate 6 is provided with elongated bolt or screw holes 6^a with which are 105 adapted to be engaged fastening screws or bolts whereby the plate is adjustably secured to the latch post and together with the latch plate 1, may be adjusted vertically to compensate for any sag or leaning which may 110 occur in the gate or latch post. The elongated pin receiving aperture 8 in the latch

lug 7 will prevent any binding of the latch pin which might be occasioned by the sagging of the gate or leaning of the post.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as defined in the appended claim.

15 Having thus described my invention, what I claim is:

The combination with a latch post, and a gate mounted to swing past said post, of a latch plate secured on the end of the gate 20 and provided near its upper and lower ends

with lugs projecting toward the post, a vertically slideable latch pin mounted in said lugs and provided at its upper end with a handle adapted to rest upon the upper lug and provided at its lower end with an aperture adapted to receive a locking device, a stop on the latch pin between the lugs, and a keeper plate secured to the post and provided with a lug projecting into the path of the latch pin and having its sides diverging downwardly from its center and having an aperture at its center adapted to receive the end of the latch pin.

In testimony whereof I have hereunto set my hand in presence of two subscribing witnesses.

ROBERT W. GEE.
